CIGARETTE HUMIDIFIER

Frank J. Bosman, Aberdeen, S. Dak.

Application July 11, 1956, Serial No. 597,134

2 Claims. (Cl. 299—24)

The present invention relates to new and useful improvements in humidifiers particularly for cigarettes, although it will be understood, of course, that the device may also be used for moistening cigars and pipe tobacco.

The primary object of the invention is to provide, in a manner as hereinafter set forth, a humidifier of the character described which is adapted to be readily inserted in a package or case from which one cigarette has been removed for keeping all of the remaining cigarettes uniformly moist and in good condition until used.

Other objects of the invention are to provide a cigarette humidifier of the aforementioned character which will be comparatively simple in construction, durable, compact, highly efficient and reliable in use, attractive in appearance and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

Figure 1 is a perspective view, showing a humidifier embodying the present invention in use in a cigarette package, a corner portion of the latter being broken away;

Figure 2 is a view in vertical section through the device;

Figure 3 is a view in horizontal section, taken substantially on the line 3—3 of Figure 2; and

Figure 4 is an enlarged view in vertical section through an intermediate portion of the device, taken substantially on the line 4—4 of Figure 3.

Referring now to the drawing in detail, it will be seen that the embodiment of the invention which has been illustrated comprises an intermediate section in the form of a tube 5 of suitable material, preferably plastic, which tube may be of any desired dimensions. The tube 5 terminates in externally reduced and threaded end portions 6. The tube 5 further includes an angular bore 7. A longitudinally elongated radial vent 8 in the tube 5 communicates with the bore 7 at the angular intermediate portion thereof. This is shown to advantage in Figure 2 of the drawing. It will be noted that the bore 7 angles away from the vent 8. The tube 5 is still further provided, on opposite sides of the bore 7, with relatively small parallel passages 9.

Threadedly mounted on the lower end portion 6 of the tube 5 is an elongated container 10 in the form of a transparent cap for the reception of water to the desired level, as indicated at 11. Threadedly mounted on the upper end portion 6 of the tube 5 is a removable, elongated container 12 in the form of a cap for the reception of a filler 13 of cotton or other suitable soft, absorbent material. Mounted on the upper portion of the container 12 is a suitable clip 14 for securing the device in position in a cigarette package, as indicated at 15.

2

Mounted in the angular bore 7 of the tube 5 is a wick 16 of suitable material. The wick 16 is of a considerably greater length than the tube 5 and the end portions of said wick extend into the caps or containers 10 and 12.

5 It is thought that the use of the device will be readily apparent from a consideration of the foregoing. Briefly, the container 10 is removed from the tube 5, filled to the desired level with water, as at 11, and replaced on said tube. The package 15 is opened in the usual manner and a cigarette is removed therefrom. The size and shape of the humidifier is such that it may be readily inserted in the space left by the removed cigarette. The clip 14 engages the upper portion of the package 15 for securing the humidifier therein at all times. Of course, the water

10 in the container 10 saturates the wick 16 and feeds upwardly therein by capillary attraction into the absorbent filler 13 in the container 12. The air in the package 15 contacts the saturated wick 16 through the vent 8 and is moistened thereby in an obvious manner, thus moistening

15 the cigarettes, as indicated at 20. It will be noted that the vent 8 and the clip 14 are on diametrically opposite sides of the device for preventing said vent from being closed or obstructed by the walls of the package 15 when said clip is engaged therewith. The container 10 is pref-

20 erably filled with water substantially to the level of the bore 7 of the tube 5 with the device resting in a horizontal position. In this manner, the water is prevented from draining by gravity from the humidifier if the device is left in a horizontal position. Also, the angular shape of

25 the bore 7 assists in preventing the escape of the water should the device be left in a horizontal position with the vent 8 lowermost. The passages 9 permit the circulation of air between the containers 10 and 12.

30 The foregoing is considered as illustrative only of the principles of the invention. Further, since numerous modifications and changes will readily occur to those skilled in the art, it is not desired to limit the invention to the exact construction and operation shown and described,

35 and accordingly, all suitable modifications and equivalents may be resorted to, falling within the scope of the invention as claimed.

40 What is claimed as new is as follows:

1. A humidifier for insertion in a cigarette package, said humidifier comprising: a tube having a vent therein at an intermediate point, said tube further having a bore angled away from the vent and communicating therewith, a container, for the reception of water, removably mounted on one end portion of the tube, a container removably mounted on the other end portion of said tube, an absorbent filler in the second-named container, and a wick mounted in the bore of the tube and having its end portions extending into the first and second-named containers.

45 2. A humidifier for insertion in a cigarette package, said humidifier comprising: a tube having a radial vent therein at an intermediate point, said tube further having longitudinal air passages extending therethrough, removable containers threadedly mounted on the end portions of said tube, one of said containers for the reception of water and being transparent, an absorbent filler in the other container, and a wick mounted in the tube and extending therefrom into the containers.
